UNITED STATES PATENT OFFICE.

ALEXANDER T. FISCHER, OF DETROIT, MICHIGAN, ASSIGNOR OF ONE-THIRD TO CAROLINE FISCHER AND ONE-THIRD TO MARY FISCHER, BOTH OF DETROIT, MICHIGAN.

APPARATUS FOR DEFLECTING FIRE OF FIREARMS.

1,348,987.

Specification of Letters Patent. Patented Aug. 10, 1920.

Application filed February 28, 1919. Serial No. 279,839.

To all whom it may concern:

Be it known that I, ALEXANDER T. FISCHER, citizen of the United States, residing at Detroit, county of Wayne, State of Michigan, have invented a certain new and useful Improvement in Apparatus for Deflecting Fire of Firearms, and declare the following to be a full, clear, and exact description of the same, such as will enable others skilled in the art to which it pertains to make and use the same, reference being had to the accompanying drawings, which form a part of this specification.

My invention has for its object the construction of a multiple deflecting device for fire arms arranged in a carrier so that a cone of fire may be directed in any desired direction or angle of elevation and at the same time shelter the operators from hostile fire and it consists in the construction and arrangement hereinafter described and claimed.

In the drawings:

Figure 1 shows the device in side elevation mounted upon its platform.

Fig. 2 is a top plan view of the device looking down upon the device as shown in Fig. 1.

Fig. 3 is a vertical sectional view.

Fig. 4 is a cross section of the forward casting taken on line 4—4 of Fig. 3.

Fig. 5 is a fragmentary vertical sectional view showing the forward and rearward castings with the deflecting device carried therein.

Fig. 6 is a section representing a modified form of coupling to the deflecting tube.

Fig. 7 is a vertical sectional view of one of the hand screws with friction member for contact with the stationary base.

Fig. 8 is a sectional view taken vertically along the longitudinal axis of the gears used in the elevation carrier.

Fig. 9 is a side view of a modification showing the various deflecting devices arranged in a vertical plane rather than in a longitudinal one.

Fig. 10 is a front elevation of the modification shown in Fig. 9.

Fig. 11 is a sectional view taken on the line 11—11 of Fig. 10.

Similar numerals refer to similar parts throughout the several views.

In Fig. 1 numeral 1 designates the carrier made in the form of a tank container with inlet 2 and outlet 3. 4 is an upright standard two of which are provided as indicated in Fig. 2. The carrier is supported between said standards by trunnions 5 by means of which said carrier is permitted to tilt from its normal horizontal position, said tilting being regulated by means of gears 6 and 7, regulated by escapement 8, which is in turn controlled by a spring 9 and lever 10 is adapted to operate the gears and escapement, or the movement may initiate with the escapement by means of escapement lever 11. 4^a and 4^b are braces for upright standard 4. Rotatable platform 22 which carries the device is supported upon a bearing plate 12 which carries a multiplicity of balls 13 and is in itself superimposed upon a stationary platform 14. Said rotatable table is further provided with hand screws 15 provided at their lower extremities with frictional bearing plates 16 to establish a frictional contact with the stationary platform 14 and thus prevent the device from rotating when said screws are fastened down. 17 and 18 respectively are forward and rearward chains for maintaining the desired elevation of the device. 18^a is a hook for receiving the links of said chain 18 and attached to the table 22, 19 being a turn-buckle for tightening the forward chain. 20 is a cover plate shown here as bolted or screwed to the carrier 1. 21 is the projecting end of the deflecting devices.

Fig. 2 is a top plan view of the device as in Fig. 1 and is self explanatory.

Fig. 3 is a vertical sectional view of the device showing the firearm 23 telescoped within the carrier 1^a and 1^b are forward and rearward castings forming end pieces of the carrier proper and constituting the means of support for the deflecting devices. Covering plate 20 is shown fastened down on the carrier. A cross section of the bearing 12 and the ball bearings 13 is likewise shown, also the central support shaft 24 and the rotatable table 22. Perforations of the end castings which do not extend all the way through but rather in a honey-comb like manner are shown in longitudinal section at 25.

Fig. 4 is a vertical cross section of one of

the end castings taken on the line 4—4 of Fig. 3. The view is self explanatory. It shows the opening 21^a in the end casting through which the deflecting devices protrude, and the honey-combed perforations 25 before mentioned, which form that part of the circulatory water cooling system which is used to cool the end castings.

Fig. 5 is a fragmentary sectional view of 10 the forward and rearward castings vertically through one of the deflecting devices 21 and showing a modification of the method of inserting the firearm in the device. In this view the firearm 23 is shown as threaded on its outer surface and screwed into the device.

Fig. 6 is a fragmentary vertical sectional view through one of the deflecting devices of the rearward casting, which shows an 20 other method of inserting the firearm as distinguished from the methods shown in Figs. 3 and 5. In this instance it is accomplished by means of a joining member 26 provided with set screws 26^a and 26^b. The 25 deflecting device 21 in this instance must project beyond the end of the rearward casting, and the joining member 26 is then fastened by means of the set screws 26^a and 26^b to the rearward projecting end of said 30 deflecting device and the muzzle of the rifle as illustrated.

Fig. 7 is a vertical sectional view taken 35 through one of the hand screws 15, projecting through the rotatable table 22 showing the frictional bearing plate 16, and the method of applying the friction to the lower stationary platform 14.

Fig. 8 is a vertical sectional view through 40 the axes of the gears. 5 is the trunnion on which the device operates, 6 and 7 are the gears respectively, 10 the hand lever shown in side plan view in Fig. 1, 27 the shaft on which the lower gear 7 and hand lever 10 are carried being held on by means of a 45 nut 27^a.

Fig. 9 is a side plan view of a modification 50 showing the deflecting devices arranged in vertical tiers rather than in a longitudinal plane. Similar numerals refer to similar parts heretofore shown and described and it is thought the drawing is self explanatory.

Fig. 10 is a front elevation of the same 55 modification shown in Fig. 9 showing two tiers of vertically arranged deflecting devices, the curvature being downward as shown in Fig. 9, and it is thought this view is easily understood as Fig. 9.

Fig. 11 is a cross sectional view taken on 60 the line 11—11 of Fig. 9 through two of the deflecting devices 21 and through the barrels of inserted firearms 23. Method of inserting by means of a joining member 26 as shown in Fig. 6 and hereinbefore de- 65 scribed, is here illustrated.

It will become plain from the above description that the multiple deflecting devices are so arranged in a carrier that the cone of fire may be directed in any desired direction, or at any angle of elevation, 70 further that a sheath of fire may be provided so as to form an ellipse whose longitudinal axis will extend either vertically or longitudinally or any desired angle therefrom.

The carrier it will be observed is adapted 75 to fire in any desired direction by means of the rotatable table provided. The trunnion 5 with its operating gears 6 and 7, regulated by escapement 8 or by means of the hand 80 lever 10 provides means for obtaining the desired angle of elevation, the device being retained at the angle thus obtained by means of chains 17 and 18, the desired length of chain 18 being regulated by means of a 85 hook 18^a attached to the rotatable table and adapted to grasp a link in the said chain, the tension of the forward chain is more carefully regulated by means of a turn-buckle 19. The desired shape of the cone of fire 90 may be secured by turning the individual deflecting devices in the carrier so that the curvature will be in such a direction as to produce the desired result.

The carrier is made in the form of a 95 water tank, with inlet port 2 and outlet port 3 to provide water circulation therein, and the end castings are honey-combed so as to provide a circulatory cooling system for the end castings.

The device is particularly adapted for use 100 with shotguns. It is realized that rifling of the deflecting device is impracticable. By virtue of the curvature there will of necessity be an escape of the propulsive gas 105 and consequent lessening of the velocity and shortening of the effective range. Used with smooth bore firearms however, which throw a number of projectiles at one discharge at a short range, the device provides a means 110 for controlling the cone of fire as to density and direction.

It is furthermore apparent from the description that the device if used behind protected earthworks would permit the user 115 to remain entirely concealed behind such works during its operation.

Having thus described my invention what I claim is:

1. In a device of the class described, a 120 gun platform, a rotatable table mounted thereon, friction plates carried by said rotatable table adapted to be forced against said platform so as to position said rotatable table thereon, a gun carrier mounted on said 125 rotatable table comprising a tank adapted to contain water, a series of curved barrels mounted in said tank projecting there-through and extending beyond the forward end thereof, said tank adapted at the rear of 130

each of said curved barrels to receive the muzzle of a firearm in such a manner that the bore of the curved barrel will form a prolongation of the bore of the firearm.

5 2. In a device of the class described, a stationary platform, a rotatable table mounted thereon, upright standards carried by said table, a tank adapted to serve as a carrier pivoted on trunnions between 10 said upright standards so as to tilt either way from the horizontal, an escapement and gear mechanism adapted to rotate said trunnions so as to tilt said carrier, means for locking said trunnions in any position 15 to which they may be moved, means for locking said rotatable table to said plat-

form at any position to which the same may be rotated, a series of curved barrels extending longitudinally through said tank, the curved extremities thereof projecting 20 beyond the forward end of said tank, the rearward end of said tank provided with screwthreaded perforations in axial alignment with said curved barrels, each of said screwthreaded perforations adapted to receive the muzzle of a firearm in such a manner that the bore of the curved barrel will serve as a prolongation of the bore of said fire arm.

In testimony whereof, I sign this specification.

ALEXANDER T. FISCHER.
